UNITED STATES PATENT OFFICE.

JOSEPH W. NORCROSS, OF LOCKPORT, NEW YORK.

PULLEY-BLOCK.

SPECIFICATION forming part of Letters Patent No. 243,952, dated July 5, 1881.

Application filed May 16, 1881. (No model.)

To all whom it may concern:

Be it known that I, JOSEPH W. NORCROSS, a citizen of the United States, residing at Lockport, in the county of Niagara and State 5 of New York, have invented new and useful Improvements in Pulley-Blocks, of which the following is a specification.

This invention consists in the combination, in a pulley-block, of wooden sides or cheeks, 10 metallic frames or straps secured to the outer surfaces of said cheeks, lugs extending from the metallic frames or straps beyond the inner edges of the cheeks, inside metallic straps extending through the lugs, a cap provided with 15 slots to catch over the ends of the inside straps, and a key for locking the parts together. With the key is combined a pin provided with 20 grooves, which engage with the edges of the holes in the inside straps, so as to prevent the straps from spreading or from bending inward.

This invention is illustrated in the accompanying drawings, in which Figure 1 represents a face view of my pulley-block. Fig. 2 is a vertical section in the plane $\alpha\alpha$, Fig. 1. 25 Fig. 3 is a horizontal section in the plane $\gamma\gamma$, Fig. 1. Fig. 4 is an end view of the outside metallic frame. Fig. 5 is a plan of the cap detached. Fig. 6 is a face view of one of the inside straps detached.

30 Similar letters indicate corresponding parts.

In the drawings, the letters A A designate the wooden sides or cheeks, which are of the usual form or shape. To the outer surface of each of these cheeks, is secured a metallic 35 frame, B, which is, by preference, provided with a flange, a, that hugs the edge of the cheek; but these flanges may be left off, or, if desired, simple straps may be substituted for the frames. Each of these outside frames or straps is provided with two lugs, b b, which project beyond 40 the inner edges of the cheeks, A, and are provided with slots c, Fig. 4, through which extend the inside metallic straps, C C, each of the cheeks being provided on its inner surface 45 with a groove or recess for the reception of said inside straps. The outside frames or straps and the inside straps are provided with holes for the reception of the center pin, d, on which is mounted the sheave D.

50 E is the cap, (see Fig. 5,) which is provided with two slots, e e, adapted to catch over the

ends of the inside straps, C C, and with a central slot, f, to make room for the hook F. The cap E is locked by means of a key, G, which extends transversely through holes or slots g 55 in the inside straps, and which forms the support for the hook F. This key may be made in any suitable manner; but I prefer to construct the same in two parts, h i, each of which forms a wedge rounded on its outside and flat 60 on its inside, (see Fig. 2,) so that when the two parts are placed together they form a round pin. The upper part, h, of the key is provided with grooves j j, one at each end and at such a distance apart that they can be made to engage with edges of the holes or slots g in the inside straps, C C, and by inserting the lower part, i, the part h is driven up and the cap E down, and all the parts are firmly locked together. The object of the grooves j j is to prevent 65 the ends of the straps from bending either inward or outward.

In the example shown in the drawings the inside straps of both cheeks are connected at one end by a cross-piece, k, which is perforated 75 with a hole, l, Fig. 2, to receive the becket; but instead of this construction the straps may be made detached from each other, and a second cap may be applied, the same as above described.

80 The outside frame or strap is provided with a hub, m, which extends clear through the cheeks and abuts against the inner surface of the inside strap, C, (see Fig. 2,) so that the journal of the center pin runs in a continuous 85 metallic bearing. The hub m is, by preference, eccentric, as shown in Fig. 1.

By these means a pulley-block is obtained which is strong and durable and not liable to get out of order. My invention is also applicable to double or multiple blocks by extending the cap or caps across all the cheeks in the block.

90 My invention is further applicable to pulley-blocks constructed of outside frames or sides 95 with inwardly-projecting flanges or lugs b b, and with hubs, and of inside straps which extend through slots in the lugs b b, the whole being locked together by the keys G. In this case no cheeks are required.

100 What I claim as new, and desire to secure by Letters Patent, is—

1. The combination, substantially as herein-before described, of the wooden sides or cheeks, the metallic frames or straps secured to the outer surfaces of said cheeks, the lugs extending from the outside frames or straps beyond the inner edges of the cheeks, the inside metallic straps extending through the lugs, the cap provided with slots to catch over the ends of the inside straps, and the key for locking the parts together.

2. The combination, substantially as herein-before described, of the wooden sides or cheeks, the outside metallic frames or straps, the lugs extending from the outside frames or straps beyond the inner edges of the cheeks, the inside metallic straps extending through the lugs, the cap provided with slots to catch over the ends of the inside straps, the tapering pin *h*, provided with grooves to engage with the

edges of the holes or slots in the inside straps, 20 and the key *i*, for locking the parts together.

3. The combination, substantially as herein-before described, of the metallic frames or sides, the inside straps, the lugs *b b*, projecting from said frames or sides extending through said 25 lugs, the hubs or bearings formed on the frames or sides extending inward toward the inside straps, the center pin which forms the axle of the sheave, and the key or keys for locking the block together.

In testimony whereof I have hereunto set my hand and seal in the presence of two subscribing witnesses.

JOSEPH W. NORCROSS. [L. S.]
